UNITED STATES PATENT OFFICE.

WALTER ALDERDICE, OF NEW YORK, N. Y., ASSIGNOR TO MERGENTHALER LINOTYPE COMPANY, A CORPORATION OF NEW YORK.

SLUG-CASTING MACHINE.

1,379,892.

Specification of Letters Patent. Patented May 31, 1921.

Application filed August 21, 1919. Serial No. 318,887.

To all whom it may concern:

Be it known that I, WALTER ALDERDICE, a citizen of the United States, residing at New York, in the county of New York and State of New York, have invented certain new and useful Improvements in Slug-Casting Machines, of which the following is a specification, reference being had therein to the accompanying drawing.

10 This invention relates to typographical machines, such as linotype machines of the general organization represented in U. S. Letters Patent to O. Mergenthaler, No. 436,532, wherein circulating matrices are released from a magazine in the order in which their characters are to appear in print and then assembled in line, the composed line transferred to the face of a mold, the mold filled with molten metal to form a 15 slug or linotype against the matrices which produce the type characters thereon, and the matrices thereafter returned through a distributing mechanism to the magazine from which they started. As the slugs are successively cast, they are ejected from the mold and discharged into a receiving galley, wherein they are assembled side by side in a row or column under the influence of a 20 periodically operated stacking device.

25 In these machines, as heretofore constructed, the galley is arranged to receive the slugs directly from the mold and in the plane of their delivery, but the direction in which the slugs are advanced in the galley differs 30 according to language. Thus, for English, the slugs (whose type characters read from left to right) are stacked toward the left, while for languages such as Hebrew, Yiddish, Arabic, etc., the slugs (whose type 35 characters read from right to left) are stacked toward the right; hence, two different galley mechanisms are generally employed, one wherein the galley proper extends toward the left for the English machines, and the other wherein the galley proper extends toward the right for the 40 Hebrew machines. In these latter machines, due to the presence of other parts, the length of the galley is considerably less 45 than that of the former machines and is capable of holding only about one-third the number of slugs.

50 My present invention is intended to overcome the foregoing objections and aims to

render the Hebrew machine capable of handling as many slugs at a time as the ordinary English machine. The invention is also designed to obviate the necessity of employing different galley mechanisms for the two machines and contemplates a form of galley mechanism adapted to either machine and which will permit the casting therein of slugs bearing either English or Hebrew characters, as desired, a result which I believe I am the first to achieve.

The manner in which these and other results are attained will be fully pointed out in the detailed description to follow:

I have herein shown my invention merely in preferred form and by way of example, and obviously many changes and variations may be made therein without departing from its spirit. I therefore desire it to be understood that I do not limit myself to any specific form or embodiment except in so far as such limitations are specified in the claims.

Referring to the drawings:

Figure 1 is a perspective view of a portion of a linotype machine having my invention applied thereto;

Fig. 1^a illustrates a modification;

Figs. 2, 2^a and 3 are detail-views;

Fig. 4 illustrates the use in the machine of the ordinary English galley; and

Fig. 5 is an enlarged detail-view similar to Fig. 2 and showing parts in different position.

As usual, the slugs X are cast in the slotted mold A (shown in dotted lines) carried by the disk A¹ which is rotatably mounted on the mold-slide A² so as to locate the mold first in a horizontal position for casting and then in the vertical position shown for the ejection of the cast slug. During the casting operation, the mold is closed at the front by a composed line of matrices presented thereto by the first elevator (not shown) attached to the upper end of the slide A³ reciprocating in the customary guideways of the vise frame A⁴. The ejection of the cast slug is effected by the ejector A⁵ which advances from the rear and carries the slug forwardly through a port opening A⁶ in the vise frame for delivery to the galley B supported on arms or brackets B² projecting forwardly from the vise frame.

In accordance with my invention, and un-

like prior constructions wherein the slugs are delivered directly to the galley and in the plane of their delivery, I provide means to receive the slugs as they are delivered 5 from the mold and transport them to some distant point and then deliver them into the galley which is there arranged free of other parts and may therefore be of any desired length. In the present instance, and refer- 10 ring to Fig. 1, such means are in the form of an inclined chute or trough C extending for a portion of its length laterally across the machine in a direction at right angles to the plane of delivery of the slugs and for 15 the remaining portion of its length in a direction parallel to said plane, as clearly shown in said figure. The chute C is supported in position by a plate C¹ rising from the rear wall of its laterally extending por- 20 tion and formed with tapered slots or openings C² fitted over the usual galley sustaining pins or screws A⁷ on the vise frame A⁴ so as to permit the chute to be applied to and removed from the machine freely and 25 at will. The laterally extending portion of the chute has its bottom wall extended past and below the port opening A⁶ so that the slugs may drop thereon as they are delivered through said opening from the mold 30 (see Fig. 2), the front and rear walls being separated sufficiently to allow the slugs to pass by gravity down the chute on their side faces in an endwise direction as required. The forwardly extending portion of the 35 chute has its side walls more closely ar- ranged so as to guide the slugs in an edge- up position, being twisted or rifled as it emerges from the other chute portion to turn the slugs into such position as they 40 pass therefrom. This twisting and forward extension of the chute is to accommodate the form and arrangement of the galley B, which is designed to support the slugs on their bottom edges as distinguished from on 45 end in upright position as in another com- mon form of galley, and one which may be employed if desired.

As the slugs enter the galley B, they are advanced toward the right therein against 50 the resistant B¹ by a supplemental stacking lever D, pivoted at one end as at D¹ to a bracket A⁸ attached to the vise frame A⁴, and carrying at its opposite end a slug-en- 55 gaging plate D² arranged to reciprocate within the galley, it being noted that the lever is bent or curved as at D³ to avoid in- 60 terference with the chute C. The stacking lever may be operated in any desired man- 65 ner: As herein illustrated, it is rocked in one direction by a spring D⁴ attached there- 70 to at one end and to the galley bracket B² at the opposite end, and in the opposite direction by the well known justification lever G through the medium of a bell crank lever D⁵ pivoted on the machine frame and

arranged with its vertical arm in engage- 75 ment with a set screw D⁶ projecting later- ally from the stacking lever.

In the foregoing arrangement, it will be noted that the slugs are delivered from the 70 mold in vertical position and in an edgewise direction whereas they pass down the chute C on their side faces and in an endwise di- 75 rection. Means are therefore provided to act upon each slug as it is delivered from the 75 mold to cause it to tilt or fall over side- 80 wise in its passage to or down the chute. Preferably, and as herein shown, such means include a stop arranged to engage the 85 slug at the left side near its upper end and a reciprocating member arranged to engage the slug at the right side near its lower end, these parts by their coöperation thus posi- 90 tively effecting the tilting of each successive slug so that it will pass down the chute and 95 enter the galley with its lower end foremost. The stop referred to is in the form of a right angle piece E having its vertical shank por- 100 tion secured to the chute plate C¹ by means of a screw C³ and having its horizontal por- 105 tion extended forwardly in position to en- gage the side faces of the slugs at the left in the manner required. The reciprocating member is constituted by the usual or main 110 stacking lever F operated in the usual way and which for the intended purpose has its 115 slug-engaging plate F¹ adjustably mounted thereon so as to be set at a backward incli- 120 nation to engage the slug at its lower end, the plate being held in its adjusted position by means of a screw or similar device F² (Fig. 3). The action of the parts is best 125 illustrated in Fig. 2, where it will be seen that as the slug is delivered from the mold, it drops vertically onto the inclined bottom of the chute C and is engaged at the left near its upper end by the stop E, which thus requires it to be tilted to the right in pass- 130 ing down the chute. The stop alone might be sufficient to cause the necessary tilting of the slugs, but it is insured by the stacking lever F, which at the proper time is rocked toward the left to the position shown by dotted lines, causing its inclined plate F¹ to strike the lower end of the delivered slug 135 and turn it positively about the stop E as a fulcrum. When the stacking lever is sub- 140 sequently retracted, the slug is free to continue its journey in proper position down the chute.

The stop E may be fixed immovably in 145 position provided it is located at a suffi- 150 ciently low level to engage the shortest slugs, but I prefer to have it adjustable vertically so as to correspond in position to slugs of 155 different lengths. To this end, the shank portion of the stop E is formed with an 160 elongated slot E¹, wherein the set screw C³ 165 engages, and which permits it to be raised and lowered with reference to said screw, 170

which is merely loosened and tightened before and after such adjustment.

In Figs. 1^a and 2^a, which illustrate a modification, the parts are substantially the same in construction and operation as those described above, such changes as are made being intended to simplify and to reduce the cost of manufacture of the parts and to permit them to be more easily applied and with less change to the regular linotype machine. The inclined chute or trough C as modified comprises two sections C⁴ and C⁵, the section C⁴ being attached to the vise frame A⁴ by the pins or screws A⁷ as before described, and the lower section C⁵ being supported upon one of the galley brackets B² which are of slightly different form. The lower chute section C⁵ has its left side wall pivoted at its upper end as at C⁶, so as to be adjustable toward and from the opposite side wall to vary the width of the chute at its lower end to accommodate slugs of different thicknesses. If desired, a thumb nut C⁷ may be employed to hold the movable wall in its adjusted position. In its modified form, the supplemental stacking lever D has its slug-engaging plate D² beveled at d and is straight and pivoted at its rear end at D¹ to an extension B³ of the galley supporting bracket B², being operated through a link D⁷ from the main stacking lever F. The latter lever is also of slightly different form, having its slug-engaging plate F¹ attached by an offset arm F² to a pivot stud F³ passing through the upper end of the lever and provided with a knurled nut F⁴. This nut is splined to the stud F³ and is rotated to set the plate F¹ at the required backward inclination, in which position it is held by a pin F⁵ adapted to engage in a corresponding recess formed in the inner face of the nut. The latter is formed with a further recess which may be engaged with the pin F⁵ to hold the plate F¹ in a vertical position when desired.

As thus far described, the machine is intended to handle Hebrew and like slugs whose type characters read from right to left, since in the foregoing arrangement the slugs are delivered with their lower ends foremost to the galley wherein they are advanced toward the right. However, and as before stated, it is the further purpose of the present invention to permit the casting in the same machine of English slugs whose type characters read from left to right, and to that end there are provided means adapted to be brought into action at will for reversing the slugs end for end as they leave the mold and thus to deliver them to the galley with their upper ends foremost, so that when the slugs are advanced toward the right in the galley they will be arranged in proper order. To effect this reversal of the slugs, I make use of the stop E and the

main stacking lever F as before. However, to secure the desired result, (see Fig. 5) the stop E is adjusted to a lower level (the slot E¹ being made long enough for the purpose) where it is adapted to engage each slug at 70 the left near its lower end, while the plate F¹ of the stacking lever F is set at a forward inclination so as to engage the slug at the right near its upper end. Hence, when the slug drops onto the inclined bottom of 75 the chute C, it is struck by the plate F¹ which turns it to the left about the stop E as a fulcrum, as shown by the dotted lines in Fig. 5, and thus causes the slug to pass down the chute and enter the galley B with 80 its upper end foremost. In this way, and simply by adjusting the stop E and plate F¹, the slugs may be delivered to the galley with either end foremost, thus adapting the machine for composition in English or 85 Hebrew (or like languages) as desired.

Fig. 4 illustrates the use in the machine of the ordinary form of English galley H suspended as usual on the supporting pins 90 A⁷ of the vise frame, and wherein the slugs 95 are advanced toward the left. To use the galley H, it is merely necessary to remove the inclined chute or trough C (in its entirety as constructed in Fig. 1 or its upper section C⁴ only as in Fig. 1^a), which carries 95 with it the stop E, and to set the plate F¹ of the slug stacking lever F in a vertical position. As thus arranged, the parts provide a galley mechanism of the form common in the English machines, so that if desired this arrangement may be employed for the English slugs in lieu of the reversing devices previously described. In other words, the foregoing mechanism is such that either Hebrew or English slugs may be stacked 105 in one and the same galley, or the Hebrew slugs stacked in one and the English slugs in a different galley, the parts being arranged to secure either of these results by an easy and quick manipulation.

As previously stated, I have shown my invention only in preferred form and by way of example, and obviously many modifications and alterations therein, and in its mode of adaptation, will suggest themselves 115 to those skilled in the art and still be comprised within its scope.

Having thus described my invention, its construction and mode of operation, what I claim and desire to secure by Letters Patent, 120 is as follows:

1. In a slug casting machine, the combination of means for delivering the slugs from the mold, means to receive the slugs as they are so delivered and transport them laterally across the machine in a direction at right angles to their plane of delivery, a galley arranged to receive the slugs as they are discharged from the transporting means, and means for advancing the slugs 130

in the galley in a direction opposite to that in which they are transported across the machine.

2. In a slug casting machine, the combination of means for delivering the slugs from the mold, means to receive the slugs as they are so delivered and transport them first laterally across the machine in a direction at right angles to their plane of delivery 10 and then forwardly of the machine in a direction parallel to said plane, a galley arranged to receive the slugs as they are discharged from the transporting means, and means for advancing the slugs in the galley 15 in a direction opposite to that in which they are transported across the machine.

3. In a slug casting machine, the combination of means for delivering the slugs from the mold, a galley wherein the slugs 20 are stacked and having its entrance arranged remote from their point of delivery, an intermediate inclined chute or trough along which the slugs pass from the delivery means to the galley, the said chute 25 extending laterally across the machine in a direction at right angles to the plane of delivery of the slugs, and means for advancing the slugs in the galley in a direction opposite to that in which they are transported 30 across the machine.

4. In a slug casting machine, the combination of means for delivering the slugs from the mold, a galley wherein the slugs are stacked and having its entrance arranged 35 remote from their point of delivery, an intermediate inclined chute or trough along which the slugs pass from the delivery means to the galley, the said chute extending first laterally across the machine in a direction at right angles to the plane of delivery of the slugs and then forwardly in a direction parallel to said plane to discharge 40 the slugs into the galley, and means for advancing the slugs in the galley in a direction opposite to that in which they are transported across the machine.

5. A combination as specified in claim 4, characterized by the fact that the chute or trough therein recited has its laterally extending portion constructed to guide the slugs on their side faces and its forwardly extending portion twisted or rifled to turn the slugs into an edge-up position and discharge them thus into the galley.

55 6. In a slug casting machine, the combination of means for delivering the slugs from the mold, a galley wherein the slugs are stacked, intermediate means disposed transversely of the plane of delivery of the 60 slugs for transporting them to the galley, means for advancing the slugs in the galley in a direction opposite to that in which they are carried by the transporting means, and means arranged to act upon each slug as 65 it is delivered from the mold to cause it to tilt

or fall over sidewise in its passage to the transporting means.

7. In a slug casting machine, the combination of means for delivering the slugs from the mold, a galley wherein the slugs 70 are stacked, intermediate means disposed transversely of the plane of delivery of the slugs for transporting them to the galley, means for advancing the slugs in the galley in a direction opposite to that in which they 75 are carried by the transporting means, and a stop arranged to engage each slug at one side near one end as it is delivered from the mold and cause it to tilt or fall over sidewise in its passage to the transporting 80 means.

8. In a slug casting machine, the combination of means for delivering the slugs from the mold, a galley wherein the slugs are stacked, intermediate means disposed 85 transversely of the plane of delivery of the slugs for transporting them to the galley, and a reciprocating member arranged to engage each slug at one side near one end as it is delivered from the mold and cause it to 90 tilt or fall over sidewise in its passage to the transporting means.

9. In a slug casting machine, the combination of means for delivering the slugs from the mold, a galley wherein the slugs 95 are stacked, intermediate means disposed transversely of the plane of delivery of the slugs for transporting them to the galley, and means arranged to act upon each slug as it is delivered from the mold to cause 100 it to tilt or fall over sidewise in its passage to the transporting means, the said tilting means including a stop to engage the slug at one side near one end and a reciprocating member to engage said slug at the opposite side near the other end.

10. In a slug casting machine, the combination of means for delivering the slugs from the mold, a galley wherein the slugs are stacked, intermediate means disposed 110 transversely of the plane of delivery of the slugs for transporting them to the galley, and means arranged to act upon each slug as it is delivered from the mold to cause it to tilt or fall over sidewise in its passage to the 115 transporting means, the said tilting means including a stop adjustable to different positions so as to engage the slug at one side near either end and a reciprocating member also adjustable to different positions to engage the said slug at the opposite side near either end, whereby the slug will be presented to the galley with its upper or lower end foremost according to the adjustment of 120 said parts.

11. In a slug casting machine, the combination of means for delivering the slugs from the mold, a galley wherein the slugs are stacked, intermediate means disposed 125 transversely of the plane of delivery of the 130

slugs for transporting them to the galley and a stop arranged to engage each slug at one side near its upper end as it is delivered from the mold and cause it to tilt or fall over 5 sidewise in its passage to the transporting means, the said stop being adjustable to different positions to coöperate with slugs of different lengths.

12. In a slug casting machine, the combination of means for delivering the slugs 10 from the mold, a galley wherein the slugs are stacked, intermediate means disposed transversely of the plane of delivery of the slugs for transporting them to the galley, 15 and a stop arranged to engage each slug as it is delivered from the mold to cause it to tilt or fall over sidewise in its passage to the transporting means, the said stop being adjustable to different positions so as to engage 20 the slug at either end as desired, for the purpose described.

13. A galley mechanism for slug casting machines including, in combination, a galley proper wherein the slugs are stacked, means 25 to receive slugs as they are delivered from the mold and conduct them to the galley, a main stacking lever arranged to engage the slugs in their passage to said conducting means, and a supplemental stacking lever 30 arranged to advance the slugs in the galley as they are discharged thereinto.

14. A mechanism as specified in claim 13, characterized by the fact that the conducting 35 means therein recited are removable and replaceable by a second galley wherein the slugs are stacked by the main stacking lever.

15. A galley mechanism for slug casting machines including, in combination, a galley proper wherein the slugs are stacked, an inclined chute or trough arranged to receive the slugs as they are delivered from the mold 40 and conduct them to said galley, a stop mounted on said chute in position to engage each slug at one side near one end in its passage to the chute, a main stacking lever having 45 its slug engaging plate set at an inclination so as to engage said slug at the opposite side near its other end, and a supplemental stacking lever acting to advance the slugs in 50 the galley as they are discharged thereinto.

16. A mechanism as specified in claim 15, characterized by the fact that the chute or trough therein recited is detachably mounted so as to be removable at will and replaced

by a second galley, and by the further fact 55 that the slug engaging plate of the main stacking lever is capable of being set in a vertical position so as to advance the slugs in the substitute galley as they are delivered from the mold.

17. A galley mechanism for slug casting machines including two slug stacking levers arranged in different positions to coöperate with different galleys.

18. A galley mechanism for slug casting 65 machines including a slug stacking lever having a slug engaging plate adjustable to different operative positions thereon.

19. In a slug casting machine, the combination of means for delivering the slugs from 70 the molds, a galley wherein the slugs are stacked in edge-up position and an intermediate chute leading to the galley and constructed to guide the slugs in an edge-up position, the said chute having one of its side 75 walls adjustable toward and from the other to vary the width of the chute at the entrance of the galley to accommodate slugs of different thicknesses.

20. A combination as specified in claim 5, 80 characterized by the fact that the rifled forwardly extending portion of the chute therein recited has one of its side walls adjustable toward and from the other to vary the width of the chute at the entrance of the 85 galley to accommodate slugs of different thicknesses.

21. In a slug casting machine, the combination of means for delivering the slugs from 90 the molds, a galley wherein the slugs are stacked, and adjustable intermediate means to act upon slugs as they are delivered from the mold and cause them to pass to the galley with either end foremost as desired.

22. In a slug casting machine, the combination of means for delivering the slugs from the mold in upright position, a galley 95 into which the slugs are discharged, and means acting upon the slugs as they are delivered from the mold to cause them to pass to the galley with their upper ends foremost, the said means being adjustable to a different position to allow the slugs to pass to the galley with their lower ends foremost.

In testimony whereof, I have affixed my signature hereto.

WALTER ALDERDICE.
